UNITED STATES PATENT OFFICE

154,476

DESIGN FOR A BATHROOM FIXTURE

Norman F. Heym, Wethersfield, Conn.

Application October 9, 1947, Serial No. 141,818

Term of patent 3½ years

(Cl. D4—3)

To all whom it may concern:

Be it known that I, Norman F. Heym, a citizen of the United States, residing at Wethersfield, in the county of Hartford, State of Connecticut, have invented a new, original, and ornamental Design for a Bathroom Fixture, of which the following is a specification, reference being had to the accompanying drawing, forming a part thereof.

In the accompanying drawing—

Fig. 2 is a front elevation thereof; and

Fig. 3 is an end view thereof.

I claim:

The ornamental design for a bathroom fixture, substantially as shown.

NORMAN F. HEYM.
